UNITED STATES PATENT OFFICE

164,240

REARVIEW MIRROR HEAD

Livingston Eric Jones, Philadelphia, Pa.

Application April 2, 1949, Serial No. 1,783

Term of patent 14 years

(Cl. D14—6)

To all whom it may concern:

Be it known that I, Livingston Eric Jones, a citizen of the United States, residing at Philadelphia, in the county of Philadelphia and State of Pennsylvania, have invented a new, original, and ornamental Design for Rearview Mirror Heads, of which the following is a specification, reference being had to the accompanying drawing, forming a part hereof.

Fig. 1 is a rear elevational view of a rearview mirror head showing my new design;

Fig. 2 is a rear perspective view;

Fig. 3 is a side elevational view; and

Fig. 4 is a fragmentary sectional view of the rim portion of the mirror head with the mirror and mounting gasket shown in dotted lines.

The characteristic features of my design reside

in the portions shown by means of full lines in the drawing.

I claim:

The ornamental design for a rearview mirror head, as shown and described.

LIVINGSTON ERIC JONES.
